UNITED STATES PATENT OFFICE.

THEOBALD FRIEDRICH SEITZ AND GEORG HEINRICH SEITZ, JR., OF KREUZNACH, GERMANY, ASSIGNORS TO SEITZ-WERKE G. M. B. H., OF KREUZNACH, GERMANY.

FILTER.

Application filed March 18, 1926, Serial No. 95,724, and in Germany March 25, 1925.

In filters, particularly in deposition filters and the like, the individual filter frames are usually inserted into the filter tank from above, after the cover has been removed. In such cases the individual frames are connected at the top and bottom through their connecting pipes with the discharge passages and are rigidly joined thereto by a screw connection. A screw connection is provided for each frame at the upper and lower discharge passages, so that the lower points of connection are hidden and inaccessible and therefore cannot be regulated.

In a filter according to the present invention the filter tank is provided with a door or removable member at one side and the individual frames are inserted from that side in the direction of their length. The discharge passages are arranged at the top and at the bottom of the front of the tank so that the points of connection with the frames are always accessible and regulable. A secure connection of each individual frame is ensured thereby. Moreover by this arrangement of the connection points a connection between frame and discharge passages is effected without the risk of air-lock so that in consequence air cannot collect at the points of connection in the upper portion of the frames and be carried along from time to time with the flowing liquid.

In order to guide the individual frames securely while they are being pushed into the tank and to ensure that they shall remain at the required intervals from each other which are necessary for the uniform distribution of the filtering material on the individual frames, the distributing plates arranged at the top and bottom of the filter tank, and preferably perforated, are constituted by corrugated plates in the corrugations of which the plates are guided, if necessary with the assistance of suitable sliding members or rollers.

Such filter tanks as that of the present invention may be subjected to an internal or to an internal and an external pressure, and in known tanks it has already been proposed to prevent bending and breaking of the walls by the provision of special strengthening irons. The manufacture of such tanks is, however, complicated and they are also very heavy. The tank forming the subject of the

present invention is manufactured or built up from separate sheets of metal whose edges are bent up and which abut against one another by means of these bent-up portions when assembled to form a wall of the tank. By this means strengthening ribs are formed which provide sufficient reinforcement for the walls. These ribs are preferably welded together but may be riveted or otherwise connected together. The ribs may be as narrow as necessary, the wall being produced from suitably narrow strips of sheet-metal with bent-up edges. If occasion demands other strengthening ribs may be arranged at right angles to these ribs, being preferably made from longitudinally folded strips of sheet metal. These strips are provided with incisions or slots at the points where they cross and bridge over the ribs of the bent plates.

Such tanks may be employed for various purposes but, in particular, they may be utilized as filter tanks.

One constructional form of a filter tank is illustrated, by way of example, in the accompanying drawings, in which Fig. 1 is a side elevation, Fig. 2 a front view with the door open or removed, Fig. 3 a view from above, partially in section, Fig. 4 a section on the line A—B in Fig. 1, Fig. 5 a perspective view of a reinforced tank, Fig. 6 a section thereof and Fig. 7 shows, in cross section, a transverse strengthening rib.

The individual filter frames are indicated by the figure 1 and the tank for receiving them by 2. The tank has a door 3 (Fig. 3) by means of which the opening 4 at the side, which serves as the opening for the insertion of the frames, may be closed. Each frame 1 carries at its front two connecting members 5, 6, each of which engages, by means of a pin 7, 8, a corresponding hole in the corresponding liquid discharge pipe or member, and each of which is packed around this hole by a packing disc 11, 12. The discharge members 9 and 10 are secured transversely at the top and bottom of the tank and communicate with pipes mounted at the outside of the tank.

Transverse bridge members 13, 14 are provided in front of each of the outlet members 9, 10 respectively, engaging at the ends in supports 15 mounted in the walls of the tank,

and each bridge-member carries a number of tightening screws 16, 17, adapted to be pressed against the corresponding connecting members 5, 6. A tight connection between the connecting member and discharge members is made thereby. It is only necessary to release the screws 16, 17, and to take out the bridges 13, 14, to enable the frames to be drawn out, each frame being provided 10 with a handle 18 for this purpose.

It will be understood, particularly from an inspection of Fig. 1, that the connecting member is so constructed and arranged that the possibility of the formation of an air lock 15 is prevented.

Each frame carries at the top and bottom of its rear end guide rollers 19, 20, respectively which travel in the corrugations of the upper and lower corrugated plates 21 20 and 22. These corrugated plates also serve as distributing plates for the unfiltered liquid, and, for this purpose, are provided with suitable perforations. The corrugated plates enable the individual plates to be inserted and maintained at exactly the required 25 intervals apart so that the intermediate spaces between the individual plates are equal and the distribution of the filter material thereon is, in consequence, uniform. 30 In place of the guide rollers suitable sliding members could be provided.

The walls of the tank are made from separate strips or plates 23 of sheet metal, which are bent up at their edges at 24. In assembling the strips to form a tank these bent edges are placed one against another, as shown in Fig. 6, and are permanently connected together by welding, for example. Vertical ribs, which strengthen the plane 40 walls of the tank, are thus formed.

At right angles to these ribs transverse strengthening bars 25 may be applied to the walls, these bars consisting preferably of folded strips of sheet metal having their 45 edges bent out at 26 (Fig. 7). The bent out edges 26 thus serve for attachment to the tank walls, by, for instance, welding. These strengthening strips are deeper than the ribs 24, and are provided at the points 50 of intersection with the slots so that they can bridge over the ribs 24. According to the size of or to the rigidity required for the tank-wall in question, these strengthening strips may be arranged more or less close 55 together. In this manner a tank is formed which has walls which can withstand internal as well as external pressure. The form of the transverse ribs 25 may, of course, be other than that suggested and might be triangular or bracket-shaped in cross section, or angle-iron or similar material might be used for this purpose. If necessary, both 60 the strengthening ribs 24 and the strips 25 may also be provided on the inside of the walls. In some cases the transverse edges 65

of the plates may also be bent and then connected together to form ribs which take the place of the separate transverse ribs.

Claims:—

1. A filter comprising a filter tank with 70 a door in a side wall, filter frames adapted to be introduced into and removed from the tank by way of the door, and means independent of and adjacent said door for connecting the frames in an accessible and reg- 75 ular manner to discharge passages.

2. A filter comprising a filter tank, filter frames adapted to be introduced thereinto by way of a side opening in the tank, a closing member for said opening, means 80 within the tank adjacent the member and independent of the member for connecting the frames to discharge passages in an accessible and regulable manner and top and bottom guide plates of corrugated material. 85

3. A filter comprising a filter tank, filter frames adapted to be introduced thereinto by way of a side opening in the tank, a movable closure for said opening, corrugated guide and distributing plates, in said 90 tank, and means within the tank adjacent said closure and independent of the closure for connecting the frames in an accessible and regulable manner to discharge passages. 95

4. A filter comprising a filter tank constructed from sheets of metal joined together at their adjacent bent up edges forming strengthening ribs, filter frames adapted to be introduced into said tank, a closable opening in the side of the tank, discharge 100 passages in said tank, means in the tank at said opening for connecting the frames in an accessible and regulable manner to said discharge passages, and distributing and guide plates in said tank substantially as described, said frames being independent of the tank parts. 105

5. A filter comprising a filter tank the walls of which are strengthened by the bent up edges of the plates from which it is constructed, transverse reinforcing members thereon, filter frames on said tank, a door at the side of the tank for the introduction of filter frames, means for connecting the frames to discharge passages and distributing plates over the filter plates and spacing 110 said frames constituted by perforated corrugated plates.

6. A filter comprising a tank, a lateral door therefor, filter frames in the tank independent of the door, inserted and removed through the door, discharge means in the tank common to said frames arranged above and below the frames at said door, and means between the frames and door to 115 effect ready connection of the frames and their discharge means.

7. A filter comprising a tank, a lateral door therefor and removable filter frames in the tank arranged perpendicular to said 120

door, filter frames inserted and removed from the tank in a horizontal direction through said door, discharge means arranged above and below the frames in the tank, removable bridges between the frames and door, and screws carried by said bridges to separately force the frames into liquid-tight contact with said discharge means, and

means for spacing the frames in the tank and also distributing liquid between them. 10

In testimony that we claim the foregoing as our invention we have signed our names this 3rd day of March, 1926.

THEOBALD FRIEDRICH SEITZ.
